FIG. 7

UNITED STATES PATENT OFFICE

2,164,618

POWDER DISPENSER

Edwin G. Masters, San Diego, Calif., assignor to
Mollie J. Masters, San Diego, Calif.

Application January 31, 1938, Serial No. 187,967

6 Claims. (Cl. 221—66)

My invention relates to a powder dispenser, for dispensing powder such as tooth powder from boxes or other receptacles which may be opened at one end for the exit of the powder, and the objects of my invention are:

5 First, to provide a substantially moisture proof powder dispenser;

Second, to provide a substantially air proof powder dispenser;

10 Third, to provide a powder dispenser to be used in connection with open ended powder receptacles, which will dispense the powder regardless of whether or not it is packed because of slight moisture;

15 Fourth, to provide a novel means of agitating the powder at the outlet of the dispenser;

Fifth, to provide a novel valve means for opening and closing the outlet to the dispenser;

Sixth, to provide novel combined means for operating both the valve and agitating means;

20 Seventh, to provide a dispenser of this class in which practically all of the working parts are enclosed;

Eighth, to provide a dispenser of this class which dispenses the powder in a long narrow stream so that it may be readily applied to a tooth brush or the like;

25 Ninth, to provide a powder dispenser of this class which is operated by a push plunger at one side but which does not operate the same with the return of the plunger; and

30 Tenth, to provide a dispenser of this class which is very simple and economical of construction, easy to operate, efficient in its action, and which will not readily deteriorate or get out of order.

With these and other objects in view as will appear hereinafter, my invention consists of certain novel features of construction, combination, and arrangement of parts and portions as will be 40 hereinafter described in detail and particularly set forth in the appended claims, reference being had to the accompanying drawing and to the characters of reference thereon which form a 45 part of this application in which:

Figure 1 is a side elevational view of my powder dispenser showing the auxiliary cap removed to facilitate the illustration; Fig. 2 is a transverse sectional view taken from the line 2—2 of Fig. 5; Fig. 3 is an enlarged sectional view of the dispenser operating plunger and its casing taken from the line 3—3 of Fig. 5; Fig. 4 is a fragmentary sectional view taken from the line 4—4 of Fig. 1 on an enlarged scale showing some of the parts in elevation to facilitate the illustration; Fig. 5 is a top or plan view of my powder dispenser complete showing the powder receptacle in connection therewith; Fig. 6 is an enlarged side elevational view of the agitator operating gear, 60

and Fig. 7 is a side elevational view of the clutch washer on an enlarged scale.

Similar characters of reference refer to similar parts and portions throughout the several views of the drawing.

5 The powder receptacle 1, powder dispenser 2, powder agitator 3, powder dispenser valve 4, powder dispenser valve arm 5, powder dispenser link 6, powder dispenser operating plunger 7, agitator operating gear 8, spring clutch 9, plunger casing 10 10 10, plunger casing spring 11, auxiliary casing 12, auxiliary casing cover 13, and tooth brush support 14 constitute the principal parts and portions of my powder dispenser.

The powder receptacle 1 may be of any conventional type.

I have shown one rectangular in shape and open at one end for pouring the contents therefrom, it being provided with a lid which may be removed and my powder dispenser casing positioned there-

20 over as shown best in Figs. 1 and 2 of the drawing, the powder receptacle being shown fragmentarily. The powder dispenser casing 2 being provided with an open beaded end portion 2a is adapted to receive the open end of the receptacle 1. This casing 2 is preferably rectangular shaped in cross section and is semi-circular shaped at its lower end as shown best in Figs. 1 and 2 of the drawing.

25 It is provided at its extreme lower end at the center with an open slot 2b which extends substantially across the lower end. It is also provided with downwardly extending central lug portions at opposite sides 2c, which are provided with holes 2d which serve as journals for the extending shafts 4a and 4b on the powder dispenser valve 4. The main seating portion of said valve

30 30 being curved as shown best in Fig. 2 of the drawing and adapted to fit under and close the slot 2b in the casing 2, the same being shown in closed position in Fig. 2 of the drawing. This valve 4, however, may be revolved on its shafts 4a and 4b so that the slot 2b is opened to permit the powder to drop out through said slot. The shaft 4a is provided on its extended end with an arm member 5 which is rigidly secured to said

35 35 shaft and extends upwardly through a slot 12a in the auxiliary casing 12, which is an extension of the side wall of the casing 2 and extends outwardly to form a casing for the operating mechanism for operating the valve 4. Pivotal connected with the upper end of the arm 5 is a link member 6 which extends substantially at right angles to the arm member 5 as shown best in

40 40 Fig. 1 of the drawing. Pivotal connected with the free end of the link member 6 is the plunger member 7 shown best in Fig. 1 of the drawing. This powder dispenser operating plunger is provided with an arm member 7a which extends downwardly and to the lower end of which is

45 45 50 55 55 60 pivotally mounted the link member 6. It is pro-

vided with a substantially horizontal portion which is provided with a gear rack 7b which meshes with a gear 8, which gear 8 is revolutely mounted on a shaft 3a, which shaft 3a is journaled in the side walls of the casing 2 and extends therethrough. Secured on the shaft portion 3a is a clutch washer 9a to which the spring 9 is secured and the opposite end of the spring 9 is engaged in ratchet relation with the side of the gear 8 so that when the plunger member 7 is moved inwardly by pressure on the head 7c, the shaft 3a is revolved and at the same time the valve 4 is rotated to open the opening 2b. The shaft 3a is provided with extended annular portions 3b and 3c in which are secured loop shaped wire members 3d which are U-shaped and the transverse portion of which extends adjacent the inner surface of the casing 2, and interposed between these members 3d are other shorter similar members 3e which provide agitation some distance from the surface of the member 2, all as shown best in Fig. 2 of the drawing. Secured to the one side of the auxiliary casing 12 is a cylindrical plunger casing 10 which extends outwardly some distance from the one side of the member 12 and is provided in its extended end with a plug 10a which is provided with a central hole 10b which forms a support for the plunger member 7. This plunger member 7 is provided with a washer 7d secured thereto and between said washer 7d and the side wall of the member 12 and around the plunger member 7 is a compression spring 11 which tends to carry the washer 7d outwardly carrying with it the plunger members 7 when released and at the same time closing the valve 4. The member 10 is provided with an extending flange 10b which is adapted to be engaged by the fingers while the thumb engages the knob 7c for pressing the plunger and operating the valve and agitating. The auxiliary casing 12 is provided with a plate cover 13 secured thereto by means of lugs 12b, 12c, and 12d and forming a covering for enclosing the agitator and valve operating mechanism.

Though I have shown and described a particular construction, combination, and arrangement of parts and portions, I do not wish to be limited to this particular construction, combination, and arrangement, but desire to include in the scope of my invention the construction, combination, and arrangement substantially as set forth in the appended claims.

Having thus described my invention, what I claim as new and desire to secure by Letters Patent is:

1. In a powder dispenser, a casing provided with a semi-circular bottom portion provided with a slot centrally at the lower extremity, a revolute valve arranged to cover and uncover said slot, means positioned at the side of said casing for revolving said valve, including an arm member secured to said valve, and link and plunger means operatively connected with said arm, said casing opened at its upper side and provided with a beaded portion adapted to receive a powder receptacle at one end.

2. In a powder dispenser, a casing provided with a semi-circular bottom portion provided with a slot centrally at the lower extremity, a revolute valve arranged to cover and uncover said slot, means positioned at the side of said casing for revolving said valve, including an arm

member secured to said valve, link and plunger means operatively connected with said arm, an agitator revolutely mounted in said casing including cross members positioned to revolve adjacent the inner surface of said casing at the lower side thereof, means connected with said agitator engageable by said plunger for operating said agitator simultaneously with the operation of said valve, said casing opened at its upper side and provided with a beaded portion adapted to receive a powder receptacle at one end.

3. In a powder dispenser of the class described, a casing provided with a semi-circular bottom portion, a slot in the lower extremity thereof extending across the same, an elongated revolute valve revolutely mounted to open and close said slot, arm, link and plunger means for operating said valve into open and closed position, an agitator revolutely mounted in adjacent relation with the inner surface of the semi-circular portion of said casing, gear and shaft means connecting said agitator with said plunger means.

4. In a powder dispenser of the class described, a casing provided with a semi-circular bottom portion, a slot in the lower extremity thereof extending across the same, an elongated revolute valve revolutely mounted to open and close said slot, arm, link and plunger means for operating said valve into open and closed position, an agitator revolutely mounted in adjacent relation with the inner surface of the semi-circular portion of said casing, gear and shaft means connecting said agitator with said plunger means.

5. In a powder dispenser of the class described, a casing provided with a semi-circular bottom portion, a slot in the lower extremity thereof extending across the same, an elongated revolute valve revolutely mounted to open and close said slot, arm, link and plunger means for operating said valve into open and closed position, an agitator revolutely mounted in adjacent relation with the inner surface of the semi-circular portion of said casing, gear and shaft means connecting said agitator with said plunger means, a casing for said plunger means, and spring means in connection with said plunger means tending to force said plunger means outwardly when released after inward pressure thereof.

6. In a powder dispenser of the class described,

a casing provided with a semi-circular bottom portion, a slot in the lower extremity thereof extending across the same, an elongated revolute valve revolutely mounted to open and close said slot, arm, link and plunger means for operating said valve into open and closed position, an agitator revolutely mounted in adjacent relation with the inner surface of the semi-circular portion of said casing, gear and shaft means connecting said agitator with said plunger means, a casing for said plunger means, and spring means in connection with said plunger means tending to force said plunger means outwardly when released after inward pressure thereof, an auxiliary casing enclosing said arm, link and plunger means.

EDWIN G. MASTERS.
